BOOT SCRAPER

John Schauer, 143rd St., R.R. 2,
Lockport, Ill. 60441

Filed July 22, 1966, Ser. No. 3,182

Term of patent 14 years

(Cl. D9—6)

FIGURE 1 is a side elevational view of a boot scraper showing my new design;

FIGURE 2 is a top plan view thereof;

FIGURE 3 is a bottom plan view thereof;

FIGURE 4 is an end elevational view thereof taken from the left of FIGURE 1;

FIGURE 5 is an end elevational view thereof taken from the right of FIGURE 1;

FIGURE 6 is a cross-sectional view thereof taken on line 6—6 in FIGURE 1.

The side opposite from that shown in FIGURE 1 is a mirror image thereof.

I claim:

The ornamental design for a boot scraper, as shown and described,
